UNITED STATES PATENT OFFICE.

JONATHAN BARTLETT, OF EPPING, AND GEORGE B. WIGGIN, OF SOUTH NEW MARKET, NEW HAMPSHIRE, ASSIGNEES OF ONE-HALF TO JOHN W. HOARD, OF PROVIDENCE, RHODE ISLAND.

PRESSER-FOOT-LIFTING DEVICE FOR SEWING-MACHINES.

SPECIFICATION forming part of Letters Patent No. 403,725, dated May 21, 1889.

Original application filed July 23, 1887, Serial No. 245,561. Divided and this application filed May 3, 1888. Serial No. 272,745.
(No model.)

To all whom it may concern:

Be it known that we, JONATHAN BARTLETT, of Epping, and GEORGE B. WIGGIN, of South New Market, in the county of Rockingham 5 and State of New Hampshire, have invented certain new and useful Improvements in Presser-Foot-Lifting Devices for Sewing-Machines; and we do hereby declare that the following is a full, clear, and exact description of the invention, which will enable others skilled in the art to which it appertains to make and use the same, reference being had to the accompanying drawings, and to letters of reference marked thereon, which form a part of this 15 specification.

Our invention relates to sewing-machines generally, but more particularly to the class of waxed-thread machines adapted for sewing shoes or other articles made from leather or 20 other kindred material; and it has special reference to the presser-foot and lifter and parts auxiliary thereto.

In the accompanying drawings, Figure 1 is a front elevation of a machine embodying our 25 invention. Fig. 2 is a side elevation. Fig. 3 is a vertical section from front to rear; Fig. 4, a detail showing lever U and adjacent parts.

Similar letters represent like parts in all the figures.

30 A is the base of the machine, and B B' are the two vertical standards for supporting the mechanism.

C is the driving-shaft, which passes through the standards B B', having the driving-wheel 35 D at one end and the cam E for reciprocating the needle at the other. Secured to the driving-shaft C, between the standard B and wheel D, is a gear, F. A small gear or pinion, G, is journaled on the standard B under 40 the gear F, and engages with said gear, while a third gear, H, engages with the gear G and is secured under said gear upon a shaft, I, which passes through the standards B B'. To the opposite end of said shaft from the gear 45 H is a cam, J, for vibrating the needle-carrying frame. Keyed to the shaft C, between the standards B and B', is another cam, K, also for a purpose hereinafter to be described. L is an oscillating frame or standard, which is

pivoted to the top of the standard B' and rests 50 against the same. This frame L has a box or casing, M, in which the cam E and other parts of the machine are adapted to work; and N is an opening in the frame L, in which revolves the cam J. The cam E is curved on 55 one side, E', and straight on the other side, E², so that when the cam revolves in one direction the curved surface will ride over and operate the blocks b b', while any turning to the opposite direction will bring the shoulder, 60 which is formed by the straight side D², in contact with the blocks and prevent any further turning in that direction.

R R' are brackets extending out beyond the front of the machine, and through vertical 65 holes in the ends of these brackets the presser-foot bar S is adapted to slide. The presser-foot S' is attached to the presser-foot bar in any appropriate way. A coil-spring, S², encircles the bar S, between the bracket R' and 70 an adjustable sleeve, S³, on said bar. The function of this spring is to press the presser-foot down upon the horn upon which the goods are placed and seen.

Pivoted to the bracket R' is a lever, T, one 75 end of which has a concave recess upon its upper side, which is adapted to press against the under side of a roller, t, journaled to the bar S above the bracket R'. To the other end of the lever T is loosely pivoted a vertical 80 rod, t'.

U is a lever, which is pivoted to the standard B' on the other side of the shaft C from the rod t', and this lever has a hole through which the lower end of the rod t' passes, and 85 which is large enough to allow of a free movement of the rod in said hole. The lower end of the rod t' is screw-threaded, and has a nut below the lever U to keep the rod and lever together and to adjust them relatively to each 90 other. The lever U passes under the cam K, and is adapted to be held against the said cam by the nut on the end of rod t'. A handle, u, is attached to the free end of the lever U to allow the presser-foot to be raised by hand. 95

The presser-foot is raised by the handle of the lever U, and the material to be sewed is placed between the presser-foot and the horn

W, when the former is allowed to drop upon the material and hold it in place. The position of the parts will then be as shown in Fig. 1. The revolution of shaft C causes the cam 5 K at the proper period to operate the lever U, and thus raise the presser-foot S', so as to allow the material or work to be fed onward. The revolution of the shaft C will also cause the shaft I to revolve through the instrumentality of the gears F G H, and just after the cam K has begun to operate the lever U to raise the presser-foot the cam J will come in contact with the rectangular piece *i* and cause the frame L to oscillate to the left. The needle-bar P being hung on this standard will also be carried to the left, and the needle being through the material will carry the same with it to the end of the stroke.

The distance of the oscillation of the frame 20 L determines the length of the feed of the material to be sewed and also of the stitch. The distance is regulated by the lever V' and screw-pin *l*, before named. By adjusting the pin *l* in the slide *k*² nearer to the fulcrum *k*, 25 a longer feed and stitch are obtained.

Our machine can be used for sewing almost any material; but it is more particularly adapted for sewing shoes, either turned or welted, the narrow edge afforded by the horizontal 30 top *v*² of the horn W being particularly adapted for welted goods.

This application being one of the divisions of our original applications filed July 28, 1887, Serial No. 245,561, we do not herein claim anything claimed either in that application or in either of the other division applications Serial Nos. 272,746 and 272,747, filed May 3, 1888. 35

We claim—

1. The combination of the presser-foot and its bar, brackets R R', frictional roller *t*, lever 40 T, vertical rod *t*', pivoted to said lever, lever U, the nut serving to hold together and to adjust relatively this lever and rod, and cam K on the revolving short driving-shaft C, these parts being all located above the table and 45 co-operating substantially as shown and described.

2. In combination with the presser-foot bar, the brackets R R', roller *t*, lever T, the rod *t*', pivoted to said lever, cam K on the short revolving driving-shaft, and lever U, having a handle on its free end and pivoted at its other end to a standard, all located above the table, substantially as and for the purposes described. 50
